COMBINED VENDING STAND AND MUSIC BOX

Wilhelm Winzen, Kolin-Rath, Germany

Application October 8, 1954, Serial No. 32,590

Claims priority, application Germany August 14, 1954

Term of patent 14 years

(Cl. D52—2)

To all whom it may concern:

Be it known that I, Wilhelm Winzen, a citizen of Germany, residing at Kolin-Rath, Germany, have invented a new, original, and ornamental Design for a Combined Vending Stand and Music Box, of which the following is a specification, reference being had to the accompanying drawing, forming part thereof.

The figure is a perspective view of a combined vending stand and music box, showing my new design.

I claim:

The ornamental design for a combined vending stand and music box, as shown.
